MASSACHUSETTS.

THREAD GUARD FOR SPINNING AND TWISTING FRAMES.

Application filed September 25, 1925. Serial No. 58,615.

This invention relates to the art of spinning and has particular reference to an improvement in spinning or thread-twisting frames of the ring type.

5 One of the outstanding objects of the present invention is to provide an improved thread guard consisting of means interposed between adjacent bobbins which effectually functions to prevent, in event of breakage 10 of the thread, the free end of the broken thread of one bobbin from coming into contact with the next adjacent bobbin.

The invention furthermore comprehends a thread guard of the character set forth 15 which includes means for mounting the same upon the frame, whereby retraction thereof from between the bobbins may be readily effected for the purpose of facilitating the tying of the broken thread or the removal and 20 application of the bobbins to the spindles.

The invention furthermore contemplates a thread guard of the character set forth which is comparatively simple in its construction and mode of use, which is comparatively inexpensive to manufacture and 25 install upon the twisting or spinning frame, and which is thoroughly reliable and highly efficient in its purpose.

With the above recited and other objects 30 in view, reference is had to the following specification and accompanying drawings in which there is exhibited one example or embodiment of the invention which is in no way intended as a limitation upon the scope 35 of the appended claims as it is to be clearly understood that variations and modifications which properly fall within the scope of said claims may be resorted to when found expedient.

40 In the drawings—

Figure 1 is a front view of a spinning or thread-twisting frame equipped with a thread guard constructed in accordance with the invention, parts being broken away to 45 disclose the underlying structure;

Fig. 2 is a transverse sectional view taken approximately on the line 2—2 of Fig. 1;

Fig. 3 is a fragmentary vertical sectional view taken approximately on the line 3—3 of 50 Fig. 1;

Fig. 4 is a fragmentary horizontal view taken approximately on the line 4—4 of Fig. 3;

Fig. 5 is a fragmentary end view illustrat-

ing the limiting stop for the movement of 55 the thread guard means;

Fig. 6 is a horizontal sectional view taken approximately on the line 6—6 of Fig. 1;

Fig. 7 is a similar fragmentary sectional view taken approximately on the line 7—7 60 of Fig. 1;

Fig. 8 is an enlarged fragmentary vertical sectional view taken approximately on the line 8—8 of Fig. 1;

Fig. 9 is a fragmentary sectional view 65 taken approximately on the line 9—9 of Fig. 8;

Fig. 10 is a sectional view taken approximately on the line 10—10 of Fig. 8;

Fig. 11 is a fragmentary sectional view 70 taken approximately on the line 11—11 of Fig. 10;

Fig. 12 is a perspective view of one of the thread-guard retaining blocks for securing the guard blades on the guard bar. 75

Referring to the drawings by characters of reference, a substantially common form of spinning or thread-twisting frame is illustrated, including end headers A and B connected by the box rail C and provided with a suitable number of middle frame members or samsons D. The spindles E for supporting the bobbins F are mounted in the usual manner in longitudinally spaced parallel relation upon the box rail C and are driven by the whorls G from the driving cylinder H. The builder rail I formed with apertures to accommodate the bobbins and having the rings J and travelers K, is raised and lowered in the usual manner by the lifter rods L, through the medium of the cam M and builder mechanism. The guard means constituting the present invention and designed as an attachment for the spinning frame, consists of a plurality of guard blades 10 mounted in such a manner as to be disposed between the adjacent bobbins F, whereby in event of breakage of one of the threads leading from the spools N to the bobbins, the loose end of the broken thread 85

on the bobbin will be prevented from contacting with the adjacent bobbins. The blades 10 are carried by a guard bar 11 which is supported from and movable for-

wardly and rearwardly with respect to the frame and builder rail. As illustrated, the guard bar 11 is suspended by hangers 12 100 from the rack bar sections 13, which are 105

mounted for horizontal sliding movement in the guides 14. The rack sections 13 are slid forwardly and rearwardly by means of the pinions 15 which mesh therewith and which are keyed to a shaft 16 journaled in the headers A and B. The shaft extends beyond said headers and has connected therewith manipulating hand wheels 17 and 18, the former being provided with a peripheral 10 radially projecting lug 18' engageable with a stop or abutment 19 on the header A to limit the sliding movement of the pinions and guard bar in their opposite directions. In order to accommodate the guard blades 10 when in their forwardly disposed active position between the spindles and bobbins E, the builder rail I is slotted forward from its rear edge at 21. This permits of the disposition of the blades 10 between adjacent 20 bobbins while allowing for vertical reciprocatory movement of the builder rail.

In view of the fact that the crowfeet O carried by the lifter rods L are each provided with a pin P projecting upwardly 25 through an aperture in the lifter rail, the guard blades 10^a which align therewith must of necessity be of lesser width than the remaining guard blades in order to obviate interference with the pins P. In order, therefore, to compensate for the decrease in width of the blades 10^a, stationary front blade sections 10^b are provided by supporting standards 22 carried by the box rail and extending upwardly through apertures 23 in the builder rail.

From the foregoing it will thus be seen that a thread guard has been devised as an attachment for a spinning or thread-twisting frame, which consists of a plurality of guard blades disposed between adjacent bobbins and spindles whereby in event of breakage of the thread leading to the bobbins from the spindles, a means is afforded for preventing the free end of the broken thread on one bobbin from flying loose and either picking up oil and splashing the thread of an adjacent bobbin or becoming entangled therewith. It is furthermore obvious that in order to facilitate the tying of broken threads or the removal and application of the bobbins to the spindles, said guard blades are mounted for rearward movement to allow for their retraction from their active positions between the spindles, such movement being accomplished by manipulation of the hand wheels 18 arranged at either end of the frame.

As illustrated, by way of example, the blades 10 are connected to the guard bar 11 by inserting the rear ends of the blades in the notches or recesses 24 formed in the front face of the bar 11, and by locking the same in place through the medium of a jamb block 25, which is retained and urged in a clamping direction by virtue of a conical-

headed screw 26. The guard bar 11 is also preferably adjustably secured to the hangers 12 by a screw 27, which passes through a horizontal slot 28 in each end of the bar 11. This permits of a shifting of the guard bar to dispose the blades centrally of each slot 21 so as to prevent contact or frictional engagement of the blades with the edges of the material defining the slots.

From the foregoing it is apparent that a thread guard for spinning or thread-twisting frames, has been devised, which is extremely simple, comparatively inexpensive to manufacture and attach, and which is highly efficient in its purpose.

What is claimed is:

1. The combination with a spinning frame, of a thread guard attachment therefor, comprising a plurality of guard blades interposed between the bobbins, and means for supporting said blades for rearward sliding movement to the retracted position from between the bobbins whereby to facilitate the tying of the threads and the application to and removal of the bobbins from the spindles, said supporting means consisting of a transversely disposed bar to which the guard blades are removably attached, rack sections to which the bar is secured, guides in which the rack sections are mounted for forward and rearward sliding movement, pinions operatively engaging the racks, a shaft to which the pinions are secured, and manipulating means at the opposite ends of the shaft for turning the same.

2. The combination with a spinning frame, of a thread guard attachment therefor, comprising a plurality of guard plates interposed between the bobbins, and means for supporting said blades for rearward sliding movement to a retracted position from between the bobbins whereby to facilitate the tying of the threads and the application to and removal of the bobbins from the spindles, said supporting means consisting of a transversely disposed bar to which the guard blades are removably attached, rack sections to which the bar is adjustably secured, guides in which the rack sections are mounted for forward and rearward sliding movement, pinions operatively engaging the racks, a shaft to which the pinions are secured, manipulating means at the opposite ends of the shaft for turning the same, and interengaging means on the manipulating means and on the spinning frame for limiting the turning movement of the shaft.

3. A thread guard attachment for spinning frames, including a plurality of guard blades interposed between adjacent bobbins, certain of said guard blades including stationary sections carried by the box rail and movable sections, and means for supporting the said movable sections together with the remaining blades for rearward sliding move-

ment to a retracted position from between the bobbins.

4. A thread guard attachment for spinning frames, including a plurality of guard blades interposed between adjacent bobbins, certain of said guard blades including stationary sections carried by the box rail and movable sections, and means for supporting the said movable sections together with the remaining blades for rearward sliding movement to a retracted position from between the bobbins, said supporting means consisting of a transverse bar, detachable means of connection between the movable sections of said certain blades and the remaining blades, rack sections, an adjustable connection between the rack sections and the supporting bar for centering the blades between the bobbins, guide elements in which the rack sections are mounted for sliding movement, pinions operatively engaging the racks, and a transverse shaft to which the pinions are secured. 45
5. A thread guard attachment for spinning frames, including a plurality of guard blades interposed between adjacent bobbins, certain of said guard blades including stationary sections carried by the box rail and movable sections, and means for supporting the said movable sections together with the remaining blades for rearward sliding movement to a retracted position from between the bobbins, said supporting means consisting of a transverse bar, detachable means of connection between the movable sections of said certain blades and the remaining blades, rack sections, an adjustable connection between the rack sections and the supporting bar for centering the blades between the bobbins, guide elements in which the rack sections are mounted for sliding movement, pinions operatively engaging the racks, and a transverse shaft to which the pinions are secured, the adjustable means of connection between the supporting bar and the rack sections consisting of longitudinally slotted portions in the supporting bar, and clamping screws extending through said slotted portions and anchored in the rack sections. 50
6. A thread guard attachment for spinning frames, including a plurality of guard blades interposed between adjacent bobbins, certain of said guard blades including stationary sections carried by the box rail and movable sections, and means for supporting the said movable sections together with the remaining blades for rearward sliding movement to a retracted position from between the bobbins, said supporting means consisting of a transverse bar, detachable means of connection between the movable sections of said certain blades and the remaining blades, rack sections, an adjustable connection between the rack sections and the supporting bar for centering the blades between the bobbins, guide elements in which the rack sections are mounted for sliding movement, pinions operatively engaging the racks, and a transverse shaft to which the pinions are secured, the adjustable means of connection between the supporting bar and the rack sections consisting of longitudinally slotted portions in the supporting bar, and clamping screws extending through said slotted portions and anchored in the rack sections. 55
